UNITED STATES PATENT OFFICE.

JOHN ELLMORE, OF ALTOONA, PENNSYLVANIA, ASSIGNOR OF ONE-HALF TO
F. B. BYERS, OF ALTOONA, PENNSYLVANIA.

JOINT FOR FLANGED BEAMS.

SPECIFICATION forming part of Letters Patent No. 711,699, dated October 21, 1902.

Application filed August 2, 1902. Serial No. 118,077. (No model.)

To all whom it may concern:

Be it known that I, JOHN ELLMORE, a citizen of the United States, residing at Altoona, in the county of Blair and State of Pennsylvania, have invented new and useful Improvements in Joints for Flanged Beams, of which the following is a specification.

The object of my invention is the provision of an improved joint for flanged metallic beams, including railroad-track rails, I-beams, channel-beams, Z-beams, bulb-beams, &c., which can be easily and quickly formed, which shall be cheap in first cost, which shall be very strong and durable, which shall admit of facile manipulation in uniting and separating the parts, and which withal shall constitute a superior means for connecting the adjacent ends of metallic or other flanged beams.

20 My invention consists in certain novelties of construction and combinations of parts hereinafter set forth and claimed.

The accompanying drawings illustrate three examples of the physical embodiment of my invention constructed according to the best modes I have so far devised for the practical application of the principle.

Figure 1 is a perspective view of the ends of railroad-track rails united by my improved joint. Fig. 3 is a section on line *xx*. Fig. 2 is a section on line *yy*. Fig. 4 is a perspective view of the ends of two I-beams fashioned to form a joint and with the ends separated. Fig. 5 is a view similar to Fig. 4, showing my invention in connection with channel-beams.

Referring to the several figures, the letter A designates the upper head or flange of a beam; B, the lower flange; C, the web; D, a tailpiece formed by removing portions of the upper head or flange and lower flange; E, the relatively long free edge of the tailpiece; F, the relatively short free edge of the tailpiece; G, an offset or knuckle; H, a clamp; I, the bolt-piece of the clamp; J, the threaded bolt end; K, the bent end fashioned to frictionally fit the flange; L, the perpendicular bearing end; M, the nut-piece of the clamp; N, the perpendicular bearing end; O, the curved end; P, the extreme end of the curved portion, frictionally engaging the surface of the

bolt end of the clamp upon its lower surface; Q, holes for bolts in the tailpiece and web, and R designates the line upon which the web is separated from the lower flange when so desired to allow the tailpiece to be offset to a plane parallel with the plane of the permanent web of the rail or beam.

It will be observed that when the ends of the rails or beams are brought together the sectional surfaces of the heads or flanges are in frictional contact and that the tailpiece of one rail or beam laps over the end of the other rail or beam, and thus forms at the points where the heads or flanges are cut away a web of double thickness or two webs.

From the foregoing specific description, taken in connection with the drawings, it is obvious that I have produced a joint for flanged beams which fulfills all the conditions set forth as the object of my invention.

While I have shown only three examples of the physical embodiment of my invention, I do not thereby intend to limit the scope thereof to such examples, inasmuch as modifications may be introduced in practice without constituting substantial departures.

What I claim as new, and desire to secure by Letters Patent, is—

1. A joint for flanged beams comprising the ends of two beams of similar structure, each end of a beam having an offset tailpiece with a relatively long free edge and a relatively short free edge, the heads or flanges of both beams being in contact and the tailpiece of each beam overlapping the end of the other beam, and means for holding the ends of the beams in place.

2. A joint for flanged beams comprising the ends of two beams of similar structure, each end of a beam having an offset tailpiece, which overlaps the end of the other beam, the flanges of the ends of the two beams being located in line and one matching the other, and means for holding the ends of the beams together; the points of union of the flanges at the top of the joint being in a different perpendicular plane from the point of union of the flanges at the bottom of the joint.

3. A joint for railroad-track rails comprising the adjacent ends of two rails, each rail having an offset tailpiece which overlaps the

end of the adjacent rail, the heads and bottom flanges of said rails being in line and matching and with the respective points of union in different perpendicular planes, and 5 means for holding the ends of the rails in alinement.

4. The combination with jointed flanged beams in which a tailpiece of each beam overlaps the end of the other beam, of a clamp 10 comprising a bolt-piece and a nut-piece, each of said pieces having a bearing end which respectively engages the web and tailpiece of the jointed beams, and a nut for engaging the threaded end of the bolt-piece.

15 5. A clamp comprising a bolt-piece, I, having a bent end, K, and bearing end, L, and a perforated nut-piece, M, having a top bearing

portion, N, and a curved portion with an end, O, which frictionally bears against the bolt portion, and a nut for engaging the threaded 20 end of the bolt-piece.

6. The combination in forming a joint, of a flanged beam having an offset tailpiece with free edges of unequal lengths; a flanged beam having an offset tailpiece separated from the 25 lower flange on the line, R; and means for holding the ends together when joined.

In testimony whereof I affix my signature in presence of two witnesses.

JOHN ELLMORE.
